UNITED STATES PATENT OFFICE.

HERMAN C. CARVER, OF RED OAK, IOWA.

SIGN-WRITER'S APPARATUS.

SPECIFICATION forming part of Letters Patent No. 576,949, dated February 9, 1897.

Application filed May 6, 1896. Serial No. 590,434. (No model.)

To all whom it may concern:

Be it known that I, HERMAN C. CARVER, of Red Oak, in the county of Montgomery and State of Iowa, have invented a new and Improved Script-Sign-Painting Apparatus, of which the following is a full, clear, and exact description.

The object of this invention is to provide a superior apparatus for writing signs, and particularly an apparatus which will be capable of very readily and beautifully forming the various shade lines and scrolls desirable in this work. I attain this end by means of a main or body portion having a flanged mouthpiece, a block contained within the body portion and having a portion engaged with the mouthpiece to close the same, and a point passing through the block, the point serving to form the fine lines, while the block is capable of moving inwardly to permit the flange of the mouthpiece to form shaded lines.

The invention consists in certain peculiar features of construction and combinations, which will be fully described hereinafter and finally embodied in the claims.

Reference is to be had to the accompanying drawings, forming a part of this specification, in which similar characters of reference indicate corresponding parts in all the figures.

Figure 1 represents a perspective view of my invention, showing it as employed. Fig. 2 is a longitudinal section of the same, showing the parts in the position which they assume during the operation of changing from a fine to a shaded line and directly before the parts are ready to form this shaded line, the guide shown in Fig. 1 being omitted. Fig. 3 is an end elevation of the main or body portion. Fig. 4 is a sectional view on the line 35 55 of Fig. 2. Fig. 5 is a view in plan of the main or body portion and the parts within the same, the handle-tube and its connected parts having been removed. Fig. 6 is a section also on the line 55 of Fig. 2, with a hereinafter-described part removed. Fig. 7 is a diagrammatic view showing the way in which the instrument is made to form the two classes of lines. Fig. 8 is a sectional view taken through the main or body portion and a portion of the handle-tube, the view showing a

modification; and Fig. 9 is an elevation also illustrating a modification.

The body portion 11 of the apparatus is formed approximately cylindrical, with its outer end rounded and formed with a flanged 55 mouth 12, the oval or elliptical form of which may be seen in Fig. 3. Screwed into the internally-threaded inner end of the body portion 11 is the enlarged outer end of the handle-tube 13, to the opposite end of which a nipple 60 14 of the elbow 15 is connected, said elbow having communication with a reservoir 16 for the liquid used to form the signs.

The reservoir 16 is closed at the top and may thus be inverted without spilling its contents. Any suitable opening may be provided in the reservoir for filling it.

Operating in triangularly-shaped ears formed integral with the body portion 11 are the respective set-screws 17, which pass diagonally into the body portion and engage a plate 18, secured on the valve-block 19, said valve-block having at its outer portion an oval-shaped projection 20, capable of snugly fitting within the flanged mouth 12, and contiguous to the projection 20 is a packing-ring 21, adapted to bear against the inner side of the body portion adjacent to the mouth 12, so as to close the mouth 12. The block 19 is formed with a central orifice 22, the forward 80 portion of which is contracted, as best shown in Fig. 2, and extended to the front side of the block, producing an opening around which a flange 23 is formed.

The plate 18 is centrally perforated, and passed through this perforation is a threaded rod 24, the lower end of which passes into the contracted forward portion of the recess 22, and carries a point 25, which is formed with a screw-threaded shank adjustable in the end 90 of the rod 24, whereby the position of the point 25 with relation to the rod 24 may be regulated. The point 25 forwardly projects beyond the flange 23, and the purpose of the point 25 is to form the fine lines before referred to. Operating on the rod 24 and located within the recess 22 are two nuts 26, said nuts serving to limit the movement of the rod within the recess 22.

As may be seen in Figs. 2 and 5, the body 100

portion 11 is provided at its inner end with two flanges 27, said flanges being oppositely arranged and having spaces between their contiguous ends, through which spaces a plate 28 may be passed, said plate having a U-shaped yoke 29, by which it may be turned to move past the spaces between the ends of the flanges 27 and lie under said flanges.

Fig. 5 shows the plate 28, the yoke 29 being removed. The plate and the yoke 29 are orificed to receive the rod 24, and the plate is adapted to press a comparatively strong expansive spring 30, said spring bearing against the plate 18 on the block 19 and thereby pressing said block outwardly, the block being capable of inward movement, limited, however, by the screws 17.

Contained within the handle 13 is a comparatively weak expansive spring 31, said spring engaging at its outer end with the nipple 14 and at its inner end with a spider-nut 31^a, secured on the rod 24, the rod 24 also having a locking-nut 32, by which the nut 31^a may be held.

Contained within the body portion 11 are two oppositely located and curved guide-plates 33, the guide-plates being adapted to receive the ends of the block 19 and to guide the same in its movement, and the guide-plates are perforated, so that they will not obstruct the flow of the liquid used for forming the signs. The outer edges of the guide-plates 33 are formed with recesses in their middle portions, the recesses being arranged so as to leave projections at each end of each outer edge. These projections furnish means for connecting the guide-plates to the body portion, and are shown by dotted lines in Fig. 2.

Embracing the outer end of the handle-tube 13 is the yoke 34 of an arm 35, the arm projecting outwardly at right angles to the handle-tube and parallel with the mouthpiece 12. Carried by the arm 35 is a cross-bar 36, in the ends of which the screw-threaded rods 37 are respectively held, said rods having casters 38 at their lower ends, which casters are arranged to engage the surface on which the sign is formed and to support the apparatus, so that when operated to form thin lines the point 25 will alone engage the surface written on, while when the device is employed to make shaded lines the rods 37 and their casters 38 will serve to effect an even opening between the flanged mouth 12 and the surface on which the sign is formed, the point 25 still exclusively engaging the said surface.

The parts 35, 36, and 37 or their equivalents constitute a guide for the device.

Adjustably secured to the arm 35 is a supplemental arm 39, which projects laterally from the arm 35 and inward toward the handle-tube 13, said supplemental arm being adapted to engage the hand of the operator, as shown in Fig. 1, so that the operator may determine the exact degree of pressure which

he applies to the arm 35, and consequently to the surface being written on, it being only necessary to keep these points in mere contact, applying the greater part of the pressure to the point 25.

In using the invention the reservoir 16 is filled with the liquid used to form the sign, and the device is grasped, as shown in Fig. 1. The point 25 will first engage the surface, and, being pushed slightly inward by the pressure on it, will open a portion of the contracted outer end of the recess 22, so as to permit the liquid to flow around the point 25 and be applied to the painted surface, forming a line such as those indicated by the letter *a* in Fig. 7.

Should it be desired to blend the line *a* into a heavy-shade line, as indicated by the letter *b* in Fig. 7, additional pressure is applied to the handle-tube, which will cause the block 19 and the rod 24 to move inwardly against the tension of the springs 30 and 31 and the flange of the mouthpiece 12 to nearly engage the painted surface, it being understood that the point 25 still engages this surface. The paint will now flow through the space between the block 19 and the inner sides of the flange 12, and thence to the surface painted on via the space between the said surface and the flange 12, as will be fully described hereinafter, and a broad line will be formed, which line, by twisting or turning the body portion 11, may be gradually enlarged or contracted or abruptly terminated, as illustrated in Fig. 7. In this figure the projection 20 and point 25 are diagrammatically shown at various stages in the operation.

It will be seen that upon relaxing the pressure on the handle-tube 13, which pressure causes the block 19 to move inward, the block will return, and at this return, through the medium of the flange at the mouth 12, the block will so shut off the liquid that it will be forced back into the body portion 11, as contradistinguished from being pushed out through the mouth.

In forming certain styles of script the fine lines have but little curve, and to adapt the device to this work the modification shown in Fig. 8 is provided, such consisting in passing a rod 40 through the block 41, said rod extending slightly beyond the projection of the block 41 to form the writing-point. This dispenses with all of the other parts within the body portion 11, excepting the screws 42, which are similar to the screws 17 of the first form, and the side plates similar to the plates 33 in the before-described figures, which side plates are arranged and operated as described. The rod 40 is provided with a spider-nut 43 and pressed by a spring 44, contained within the handle-tube 13.

The modification shown in Fig. 9 consists in placing the reservoir 45 in axial coincidence to the handle-tube 13, contradistinguished from connecting it with the tube 13

through the medium of the elbow 15, as in the first form. The purpose of this is to adapt the instrument for use on horizontal surfaces, it being understood that the first 5 form of the invention is adapted for use on vertical surfaces, such latter use being the most common.

The liquid used to form the signs may be paint or other thickened liquid, such as whit- 10 ing combined with a proportion of gum-water, such mixture being useful for producing temporary signs.

It will be seen that the screws 17 prevent the block 19 from excessive inward movement, and the adjustment of these screws is such 15 that they will cause the nuts 26 to engage the plate 18, so that the point 25 will always engage the surface on which the sign is formed, but will prevent the flange 12 from engaging 20 this surface, since such engagement would tend to destroy the accuracy of the work. The space between the flange 12 and the said surface during the writing of broad lines is very slight, and through this space the paint 25 flows.

The spring 31 is weaker than the spring 30, and pressure on the handle-tube 13 will first move the rod 24 inward until the nut 26 engages the plate 18, whereupon the spring 30 30 will be compressed. This compression of the spring 30 will be concurrent with the inward movement of the block 19.

The casters 38 serve to permit an easy rolling movement of the rest and entirely overcome friction, so as to make the apparatus 35 effectively sensitive to the slightest movement of the hand of the operator.

The turning of the device to change the line from light to shade will not necessarily result 40 in a complete inversion of the reservoir. Accordingly the necessary pressure of the ink or paint at the writing-point will always be preserved.

Having thus described my invention, I 45 claim as new and desire to secure by Letters Patent—

1. The combination of a body portion having a flanged mouth, a block capable of closing said mouth, and a point carried by the 50 block and capable of projecting through the

mouth and of movement with the block into the body portion, substantially as described.

2. The combination of a body portion having a mouth, an orificed block capable of removably closing said mouth, and a point movable through the orifice of the block and independently thereof, substantially as described. 55

3. The combination of a body portion having a mouth, a block capable of closing the mouth, a spring pressing the block, a rod 60 passed through the block, a point carried by the rod and projecting through the mouth of the body portion, a spring pressing the rod, a nut carried by the rod and capable of engagement to move the block with the rod, and 65 a screw carried by the body portion and limiting the inward movement of the block, substantially as described.

4. The combination of a body portion having a mouth, a block capable of closing the 70 mouth, a rod passed into the body portion and block, and a point carried by the rod and projecting through the mouth of the body portion, the block being capable of movement inward to open the mouth of the body portion, substantially as described. 75

5. A sign-painter having a body portion provided with liquid-feeding devices, a guide rigid with the body portion and capable of engaging the surface on which the sign is to be 80 painted, and a supplemental arm carried by the guide and capable of engaging the hand of the operator and of indicating the degree of pressure applied to the guide, substantially as described. 85

6. The combination with a body portion having a flanged mouth, of a centrally-recessed block having a projection extending through the mouth, a rod passed into the recess of the block, a point carried by the rod 90 and projecting through the block and through the mouth of the body portion, a screw carried by the body portion and engaging the block to limit its inward movement, and means for spring-pressing the rod and block, substantially as described. 95
